SHORT-CIRCUITING CONTACTOR FOR DIRECT-CURRENT CIRCUITS

Filed Feb. 26, 1948

UNITED STATES PATENT OFFICE

2,595,251

SHORT-CIRCUITING CONTACTOR FOR
DIRECT-CURRENT CIRCUITSLawrence H. Harrison, Birmingham, Ala., as
signor to the United States of America as repre-
sented by the Secretary of the Interior

Application February 26, 1948, Serial No. 11,234

2 Claims. (Cl. 175—294)

(Granted under the act of March 3, 1883, as
amended April 30, 1928; 370 O. G. 757)

1

The invention described herein may be manufactured and used by or for the Government of the United States for governmental purposes without the payment to me of any royalty thereon in accordance with the provisions of the act of April 30, 1928 (ch. 460, 45 Stat. L. 467).

This invention relates to a short circuiting contactor for direct current circuits.

In certain portions of some electrical distribution systems, particularly in coal mines, it is essential that electrical arcs be prevented to the greatest degree possible. When a short circuit occurs on a trailing cable carrying direct current, forces are set up tending to separate the conductors. This results in an arc being drawn which in many cases limits the current to a value below the rating of the fuse which is intended to protect the cable from such damaging arcs. A condition is thus set up whereby a disastrous mine fire or explosion can originate.

It is an object of this invention to provide a means of reducing the voltage on a fault by short circuiting the voltage at a preselected location.

It is also an object of this invention to provide a contactor device particularly adapted to short circuit a fault on a direct current circuit.

Other objects will become apparent to those skilled in the art from the following specification taken in connection with the accompanying drawing in which:

Fig. 1 is a sectional elevation view of a short circuiting contactor constructed in accordance with the principles of this invention.

Fig. 2 is a schematic drawing showing one circuit arrangement in which the contactor of Fig. 1 may be used.

Fig. 3 is a schematic drawing showing a circuit arrangement in which the contactor device is operated by the fault current flowing through the frame of a utilizing machine.

In Fig. 1 there is provided a tube 10 preferably made of fiber or other insulating material. End pieces 11 and 12 are each fixed to an end of tube 10, as by a threaded connection between the ends of tube 10 and flanges 13 and 14 of the end pieces 11 and 12, respectively.

Within the tube 10 and concentric therewith are two axially aligned magnetic core members 15 and 16. Through the greater part of their length core members 15 and 16 have a diameter

slightly less than the internal diameter of tube 10. Core member 16 at its outer end, remote from core member 15, carries a shaft 20 of reduced diameter, providing a shoulder 22 which rests against the inner surface of end member 12. Core member 15 carries at its upper end, the end remote from core member 16, a flange 19 and a shaft 21. Flange 19 abuts against the up-standing flange 29 of a non-conducting annular member 32 attached to the upper surface of end member 11 by the screws constituting terminals 28 and 31. At their opposed adjacent ends, cores 15 and 16 carry end contact members 17 and 18, respectively. End members 17 and 18 have a diameter greater than the adjacent portions of cores 15 and 16 but less than the internal diameter of tube 10 so that cores 15 and 16 will freely slide therein. Core members 15 and 16 are of such a length that with flange 19 and shoulder 22 in their seated positions contact members 17 and 18 are separated by a short distance.

A flat strip winding 25 is wound helically, tightly around the tube 10. One end of winding 25 is threaded and passes through end piece 11 and annular member 32 to form terminal 28. Terminal 28 is held in position by nuts abutting against end piece 11 and annular member 32. The line conductor is also fastened to terminal 28 by a nut. The other end of winding 25 is also threaded and passes through end piece 12 to form terminal 30. Conductor 40 connects terminal 30 with screw terminal 31 in end piece 11. Terminal 30 is held in place and conductor 40 and the load conductor are fastened to terminal 30 by nuts threaded to terminal 30.

The threaded ends of winding 25 are preferably round in section. The winding 25 may advantageously be cast in helical form and slipped over the tube 10. A flexible conductor 33 connects terminal 31 with shaft 21 of core member 15. Conductor 33 has a lug at either end, one being held under terminal screw 31 and the other being held between nuts on the threaded end of shaft 21. A negative shunt conductor is connected to a lug held between nuts on the threaded end of shaft 20.

When the contactor device of Fig. 1 is installed in operating condition it is mounted vertically as shown in Fig. 1. In this condition gravity causes flange 19 of core 15 to normally seat against the

member 29, and also causes the seating of shoulder 22 against the upper surface of end member 12. This maintains the ends 17 and 18 of cores 15 and 16 at the proper spacing. It will be understood, however, that springs could be used to bias cores 15 and 16 into normal seating position and then allow installation in any position. The enlarged diameter of end pieces 17 and 18 minimizes transverse motion of the cores 15 and 16 and provides an enlarged area for electrical contact.

One method of connecting the contactor device of Fig. 1 in a distribution circuit is shown in Fig. 2 in which the contactor device 34 is shown with terminals 28 and 30 connected in series between a source of D. C. potential 35 and a load which may be a piece of utilizing machinery such as an electrical motor 39. A safety device 36, such as a fuse or circuit breaker, is shown connected in series with the contactor 34. The negative shunt conductor from core 16 is shown in Fig. 2 connected to the negative side of the power source 35.

When a current of sufficient magnitude passes between the line and load conductors and hence through winding 25, connected in a series therewith, core 16 is attracted to core 15 by the magnetic force produced in winding 25 until end 18 of core 16 contacts the end 17 of core 15. When end pieces 17 and 18 make contact, current flows between the load wire and the negative shunt wire. Since core 15 is free to move against gravity in an upward direction, cores 15 and 16, held together by magnetic attraction, may travel slightly upward together because of the momentum of the core 16.

When cores 15 and 16 make contact, the positive side of the load is connected through the negative shunt to the negative source of power source 35. This immediately eliminates the potential on the load side of the contactor and on the fault and causes a very high current to flow from the positive side of the power source through the safety device 36, cores 15 and 16, the negative shunt and back to the negative side of the power source 35. This will cause safety device 36 to positively and quickly operate to open the circuit.

Although the utilizing device in Fig. 2 may of necessity be placed in a position where arcing cannot be tolerated, such as against the working face of a coal mine, the short circuiting contactor 34 may be placed in a position where arcing is of little consequence, such as at the entry of the mine. Moreover, since the device 34 operates to close a circuit rather than open one, its operation will be attended by relatively little arcing. Since core members 15 and 16 are both free to move and since when operating there will be a large magnetic attractive force between them, they will not tend to open as by a recoil action after they have once closed.

Another method of using the contactor device of Fig. 1 is shown in Fig. 3. In this arrangement terminals 28 and 30, and hence winding 25 are connected in series between the frame of the utilizing device 40 and the negative side of power source 35. The core 16 in this case is connected to the positive side of the power source 35. A switch 37 is provided between power source 35 and utilizing device 40. A safety device 38 is connected in series with the power conductors.

When there is a fault in machine 40 and the positive wire touches the frame, a current will flow through the winding 25 and operate the contactor 34. When cores 15 and 16 make contact a short circuit will be provided across the power

source 35 and potential will be removed from machine 40. The short circuit provided by device 34 includes safety device 38 which will be operated by the large current flowing therethrough to open the circuit.

The small diameter of the coil 25 in the short circuiting contactor, described above, is conducive to high speed operation as the accelerating force on cores 16 and 15 is dependent upon the product of the amperes and the turns in coil 25. The speed of closing of the gap is inversely proportional to the inductance of the operating coil. Since the inductance of the operating coil is affected by its diameter, the small diameter permitted by this construction causes the contactor to operate at very high speed. A flat strip winding permits still further reduction in the physical diameter of the device.

The simplicity of the design makes this device particularly adaptable for cable tap service in mechanized coal mines and tends to reduce the manufacturing cost. The light weight of such a contactor, compared with the air break circuit breaker for equivalent service, would be advantageous in any portable device with trailing cables. Practice has shown a virtual absence of arcing and burning in relation to the magnitude of current handled, an advantage thought to be attributable to the position of the contacts in the magnetic field of the winding 25.

The embodiment and applications of this invention described above are exemplary only and many modifications and additional adaptations will occur to those skilled in the art within the scope of the appended claims.

What is claimed is:

1. In an electrical distribution system for use in mines, a utilizing device and a pair of transmission wires carrying direct current, one wire having a relatively low potential and the other wire having a relatively high potential, said utilizing device being connected across said low and high potential wires, there being a safety device between said high potential wire and said utilizing device, said utilizing device having a metal frame, a contactor device comprising a coil connected between said low potential wire and said frame, and a pair of axially movable cores within said coil normally separated but arranged for rapid closing when the current in said coil exceeds a predetermined value, one of said cores being connected to said low potential wire and the other of said cores being connected to said high potential wire through said safety device, said safety device being located remotely from said utilizing device and arranged to open when the current through said safety device exceeds a predetermined value.

2. The combination of claim 1, in which the utilizing device and the contactor device are located in an enclosure subject to being filled by an explosive atmosphere and in which said safety device is located in a position where it is not subject to envelopment by an explosive atmosphere.
